Primary Examiner — Manpreet Matharu*Assistant Examiner* — Suzanne Tisdell(74) Attorney, Agent, or Firm — Dossey & Jones, PLLC;
 James P. Dossey; Phillip W Black(57) CLAIM

The ornamental design for a conical grill with four legs, as shown and described.

DESCRIPTION

FIG. 1 is a frontal isometric view of the apparatus disclosed herein;

FIG. 2 is a plain front view of the apparatus of FIG. 1;
 FIG. 3 is a plain back view of the apparatus of FIG. 1;
 FIG. 4 is a plain top view of the apparatus of FIG. 1;
 FIG. 5 is a plain bottom view of the apparatus of FIG. 1; and,
 FIG. 6 is a frontal isometric view of a handle attached to grill portion of the apparatus of FIG. 1.1 Claim, 5 Drawing Sheets(56)
